SLIDE TRAY FOR PHOTOGRAPHIC PROJECTOR

John A. Baring, Golden, Colo., assignor to Honeywell
Inc., Minneapolis, Minn., a corporation of Delaware

Filed Aug. 16, 1965, Ser. No. 86,596

Term of patent 14 years

(Cl. D61—1)

FIG. 1

FIG. 2

FIG. 3

FIG. 4

FIGURE 1 is a front elevation view of a slide tray for a photographic projector showing my new design;

FIGURE 2 is a rear elevation view thereof;

FIGURE 3 is a side elevation view thereof;

FIGURE 4 is a view taken along line 4-4 of FIGURE 2 partially in section, and partially in elevation.

I claim:

The ornamental design of a slide tray for a photographic projector, substantially as shown.
